UNITED STATES PATENT OFFICE.

JAMES H. RAND, JR., OF TONAWANDA, NEW YORK.

CARD-INDEX OR REFERENCE DEVICE.

1,367,327.

Specification of Letters Patent.

Patented Feb. 1, 1921.

Application filed January 5, 1920. Serial No. 349,602.

To all whom it may concern:

Be it known that I, JAMES H. RAND, Jr., a citizen of the United States, residing at Tonawanda, in the county of Erie and State 5 of New York, have invented a new and useful Improvement in Card-Index or Reference Devices, of which the following is a specification.

This invention relates to card index or 10 reference devices of that sort in which index or reference cards or elements are retained on a display frame or panel in overlapping arrangement with exposed edges, and particularly to such devices in which the overlapping 15 ping cards or elements are arranged in two or more parallel columns on the supporting frame or panel, and in which a plurality of such panels or frames are hinged so as to swing relatively to each other, similarly 20 to the leaves of a book for exposing to view the cards or elements on any one of the frames or panels.

One of the objects of the invention is to 25 provide a device of this nature which is of large capacity and has two or more parallel columns of overlapping cards or elements on the same side of a frame or panel with the cards or elements in one column approximately registering with those in the adjacent 30 column so that opposite or registering cards or elements in adjacent columns may bear related reference matter and can be readily examined side by side at the same time. Other objects of the invention are 35 to space the columns of overlapping cards or elements on each panel or frame so that the supporting frames or panels can be mounted with the cards or elements on one panel contacting with those on the adjacent 40 frame or panel without causing the cards or elements on adjacent frames or panels to catch against each other and interfere with the swinging movement of the panels or frames; also to arrange the columns of cards or 45 elements so that a space is left adjacent to one edge of each column or between adjacent columns on the panel or frame in which are located narrow pads adapted to bear matter related to registering matter on 50 the cards or elements in the adjacent column or columns; also to provide a cover for the end or uppermost index or reference element in each column, which cover is made of celluloid or other suitable trans-

parent material and constitutes a transparent 55 protecting holder for an indicator for the column of cards or elements.

In the accompanying drawings:

Figure 1 is a front elevation of an index or reference device embodying the invention, showing one of the frames or panels in edge elevation and partly in section and showing another panel with the index or reference elements thereon in front elevation. 60

Fig. 2 is a reduced plan view showing a plurality of the panels or frames hinged on a stand or support to swing relatively to each other. 65

Fig. 3 is an enlarged fragmentary sectional plan view of one of the panels on line 3-3, Fig. 1. 70

Fig. 4 is a sectional view of one of the cover members.

A represents an upright frame or panel 75 which may be of any suitable construction adapted to support on one or both faces thereof the columns of overlapping cards or elements B. Ordinarily a plurality of these frames or panels A are hinged at one 80 edge, a, thereof in any suitable manner on a suitable stand or support C so that the frames or panels A can be swung relatively to each other like the leaves of a book from a position in which the frames or panels 85 are substantially parallel with each other to a position to expose to view the cards or elements on any one of the frames or panels. As shown, each frame or panel A is provided at its upper and lower ends adjacent to its 90 inner or rear edge with upwardly and downwardly projecting pivots D which enter suitable bearing openings in the horizontal top and bottom rails d' of the stand or support C, whereby each panel or frame is 95 adapted to swing horizontally on the stand or support C.

The index or reference elements B may be 100 cards or slips of paper having reference matter printed thereon or they may be holders on which separate cards or slips bearing the reference matter are suitably retained, both these constructions being well known. These index or reference elements can be supported on the panel or frame A in overlapping order with one edge of each element exposed to view in any suitable manner, the elements being preferably hinged on the 105

frame so that one or more of them can be raised to expose to view the underlying element. As shown, the panel or frame A is provided on each face thereof with oppositely disposed parallel channels or grooves E at the opposite edges of each column of index or reference elements into which retaining lugs or parts f at the opposite ends of each element project for retaining the elements on the panel, the elements having tongues or parts adapted to interlock with each other or rest one upon another, or the elements being otherwise constructed so as to retain them in the overlapping relation shown with one edge of each element exposed to view. The manner of supporting the index or reference elements in overlapping relation on the panel or frame does not constitute a part of this invention and any known or suitable expedient for this purpose may be adopted.

The adjacent columns of index or reference elements on each face of each of the panels or frames are separated by an intervening space G, and a similar space G' is also preferably provided at the outer edge of the frame or panel adjacent to the outer edge of the outer column of elements, and the index or reference elements in adjacent columns on the same face of each panel or frame A are so disposed that the exposed edge of each element in one column is approximately opposite to or approximately registers with the exposed edge of a card or element in the adjacent column. Thus related matter can be provided on the registering cards or elements in the two columns and the two cards or elements can be examined at the same time. For instance, both cards or elements can apply to the same person or subject and one bear certain matter and the other different but related matter pertaining to this person or subject. By this arrangement of the cards or elements, ample space for the reference matter for a particular person or subject is provided and either card or element can be examined separately or the two related cards or elements examined at the same time, as may be desired or necessary.

The overlapping cards or elements project out from the face of the supporting frame or panel A and when the frames or panels are swung together or into substantially parallel relation the cards or elements on the facing sides of two adjacent panels or frames contact with each other, and since the panels or frames swing in different arcs on their hinges, as indicated in Fig. 2, the contacting cards or elements on adjacent panels or frames slide or shift laterally face to face upon each other. In order to prevent the edges of the cards in one column on one frame from catching on the adjacent edges of the cards or elements in the diagonally

opposite column on the next panel or frame and thus injuring the cards or interfering with the swinging movement of the panels or frames, the space G between adjacent columns on each panel or frame is made at 70 least as wide as the maximum lateral shifting movement of the elements on adjacent frames relatively to each other. By this arrangement the cards in one column on one frame cannot shift relatively to the cards in 75 the diagonally opposite column on the next frame, during the swinging movement of the frames, far enough to cause said cards or elements to strike or catch on each other. The swinging panels or frames can therefore 80 be arranged close together with the cards on adjacent frames bearing against each other without danger of the cards or elements interfering or catching in the operation of the device.

The space G between adjacent columns of cards or elements on each panel or frame and a corresponding space G' at the outer edge of the outer column of cards or elements on the frame are utilized for the reception of narrow reference strips or pads H and H'. These strips or pads extend lengthwise of the columns in the spaces G G', each pad or set of strips being thus disposed adjacent to one edge of one or both 90 of the columns of cards or elements. The several strips of each pad are ruled or otherwise prepared so that each strip has a space or portion h approximately opposite to or registering with the exposed edge of each 100 card or element in the adjacent column and adapted to bear matter related to the matter on such registering card or element. The information can be written on the strips H H' and the strips removed one after another 105 from time to time, when the matter thereon is no longer needed, thereby exposing the underlying blank strips, and the pads can be replaced by new ones whenever required. The pads or strips H and H' can 110 be retained in place in the spaces G and G' in any suitable manner. For instance, as shown, the pads or strips are provided at their upper and lower ends with holes i through which studs J on the upper and 115 lower portions of the panel or frame project, the pads or strips being retained on the studs by tongues or flaps K secured to the upper and lower edges or portions of the panel or frame and having snap fasteners k 120 or other means adapted to engage the outer ends of the studs for securing the pads or strips thereon. The free edges of the cards or elements B project outwardly from the supporting frame or panel beyond the plane 125 of the outermost strips H H' so that the edges of the elements will not strike or catch on the strips when swinging the frames or panels on their hinges.

L represents a cover member for the up- 130

permost index or reference element in each column. Each of these cover members is suitably hinged on the frame or panel so that it can be lifted to expose the underlying element, and consists of a piece of celluloid or other suitable transparent material provided with a pocket or other means for holding an index card or strip *m* against the rear face of the celluloid. Matter on this card or 10 slip *m* indicating the contents of the elements in the column can be read through the celluloid, which covers and protects the card or slip. As shown, the cover celluloid is provided with marginal folds or flanges 15 for retaining the card thereon.

I claim as my invention:

1. In an index or reference device of the character described, the combination of a supporting frame, and index or reference elements retained on said frame and disposed in overlapping arrangement in parallel columns with marginal portions of the elements in each column exposed to view one above another, and with the exposed portion 20 of each element in one column approximately registering with the exposed portion of an opposite element in the adjacent column.
2. In an index or reference device of the character described, the combination of a supporting frame, index or reference elements retained on said frame and disposed in overlapping arrangement in a column with marginal portions of the elements exposed to view one above another, and a reference strip detachably mounted on said supporting frame, extending parallel with said column of elements adjacent one edge of said elements and having spaces for reference matter registering with the exposed marginal portions of said elements.
3. In an index or reference device of the character described, the combination of a supporting frame, index or reference elements retained on said frame and disposed in overlapping arrangement in spaced parallel columns with marginal portions of the elements in each column exposed to view one above another and a reference strip detachably mounted on said supporting frame, extending lengthwise in the space between said columns and having spaces for reference matter registering with the exposed

marginal portions of said elements in said columns.

4. In an index or reference device of the character described, the combination of a plurality of supporting members arranged side by side and hinged to swing in different arcs, and index or reference elements disposed in overlapping arrangement in opposite spaced columns on the opposing faces of said supporting members, the columns on each supporting member being spaced apart a distance at least as great as the maximum lateral shifting movement of said supporting members relative to each other due to the different arcs in which they swing.

5. In an index or reference device of the character described, the combination of a plurality of supporting members arranged side by side and hinged to swing in different arcs, and index or reference elements disposed in overlapping arrangement in opposite spaced columns on the opposite faces of said supporting members, each of said elements having a free edge movable toward and from the supporting member, the columns on each supporting member being spaced apart a distance substantially as great as the maximum lateral shifting movement of said supporting members relative to each other due to the different arcs in which they swing, whereby interference between the elements on adjacent supporting members is prevented in the movements of said members.

6. In an index device of the character described, the combination of a supporting member, index or reference elements retained on said supporting member and disposed in overlapping arrangement in a column with marginal portions of the elements exposed to view one above another, and a hinged cover member for the uppermost element having a transparent front wall and means for retaining a card bearing indicating matter on said cover member behind said transparent wall.

Witness my hand this 9th day of Dec., 1919.
